Hannaford

UNITED STATES PATENT OFFICE.

GEORGE MARGOLIN, OF NEW YORK, N. Y., ASSIGNOR TO BENJAMIN J. GARFUNKEL, OF NEW YORK, N. Y., DOING BUSINESS UNDER THE NAME OR STYLE OF GARVÉ.

HAT STRETCHER.

Application filed July 9, 1924. Serial No. 724,926.

To all whom it may concern:

Be it known that I, GEORGE MARGOLIN, a citizen of the United States, residing at New York, in the county of New York and 5 State of New York, have invented certain new and useful Improvements in Hat Stretchers, of which the following is a specification.

This invention which relates to a device 10 for stretching hats, either men's or women's, utilizes two blocks movable toward and from each other, the shape and size of the blocks being such as to adapt them to distend the crown of a hat whose size is to be increased. 15 In such an apparatus it is my aim to incorporate certain improvements which promote economy in construction and assembly, facility in operation, strength and durability in service, etc. 20 A preferred embodiment of this invention is set forth in the accompanying drawing in the manner following:

Figure 1 is a side view of the stretcher, partly in elevation and partly in section, 25 showing the two blocks widely separated;

Fig. 2 is a horizontal section therethrough taken on line 2--2 of Fig. 1 and looking in the direction of the arrows; and

Fig. 3 is a fragmentary detail in section, 30 taken on line 3—3 of Fig. 1.

As shown, the structure includes in its assembly a board A whereon is secured as by bolts 4 a base B of any appropriate contour. Supported on the base is a fixed block 35 C which, in turn, provides a mounting for a second block D which is movable toward and from the other. Each block preferably consists of a suitable frame 5 whereon is carried a bell 6 having the contour required 40 for engaging suitably with a hat crown.

The lower portion of the fixed block frame is provided with a transverse opening 7 wherein is mounted a cylindrical housing 8 which extends through a similar opening 45 in the movable block frame. From the fixed block frame on opposite sides of the housing are extended toward the movable block certain walls 9 having concave inner faces so disposed as to provide between them and the housing a guideway in the form of an 50 annular space 10 wherein may be slidably received a pair of bowed ribs 11 forming in effect a cylindrical head. These ribs which

depend from the movable block frame are so shaped as to surround the housing except 55 along its lower side wherein is formed a longitudinal slot 12. The lower rib edges are shown as straightened out to receive between them a plate 13 having a toothed upper edge portion which extends within the 60 housing slot. This plate may be carried between the two ribs 11 as by means of one or more pins 14.

Within the housing is a worm screw 15 adapted to co-operate with the teeth of the 65 plate 13 so as to cause the movable block to advance toward or recede from the fixed block. At its inner end this screw is rested against a pin 16 extending transversely of the housing, the opposite end of the worm screw terminating in a shaft 17 which may be of reduced diameter. The screw is held fixedly within the housing as by means of a collar 18 which is pinned or otherwise made fast to the housing, this collar surrounding 70 the shaft in such a manner as to receive end thrusts from the worm screw when the movable block is adjusted toward the other. An operating handle 19 may be applied to the shaft 17 so as to facilitate manual rotation thereof.

It is preferred that the board A shall carry a plate 20 on which are markings indicating the size to which a hat will be stretched in each of the various positions of 85 the movable block. A pointer 21 depending from the movable block so as to terminate adjacent this marking plate serves to apprise the operator of the adjustments 90 effected.

It should be obvious that rotation of the worm screw will effect through the plate 13 a relative movement between the two blocks. In any of the various positions of adjustment, the movable block is held against rotation by engagement of the plate within the housing slot 12 and also by engagement within the guideway of the head which depends from the block D. The distance of separation between the two blocks indicated 100 in Figs. 1 and 2 is rather extreme, and in ordinary practice the depending head may be relied upon to steady the movable block against any rotative tendencies.

The present hat stretcher is advantageous 105 in many respects. Its several components

may be produced and assembled at small expense, and, whenever required, substitution of one part for another may be readily effected. As defined by the claims below, 5 I desire to be protected in the special improvements characterizing this invention in whatever form it may be embodied.

I claim:

1. A hat stretcher in which are combined 10 two blocks one movable with respect to the other, a guideway extended from one block toward the other and adapted to slidably receive a portion of the latter, a housing also extended within the guideway from one 15 block toward the other and having a fast connection with one block, there being a slot extending longitudinally of the housing, screw means rotatably secured within the housing, and an element extended within 20 said slot engaged by the screw means and connected with the movable block whereby the same is shifted toward and from the other with rotation of the screw means, substantially as described.
2. A hat stretcher in which are combined 25 a pair of blocks, a slotted housing secured fast to one block and extended through the other, a toothed element connected with the latter block and extending in part through 30 the housing slot, and screw means rotatably secured within the housing in engagement with the toothed element and adapted, when rotated, to move the block to which said element is connected toward or from the other 35 block, substantially as described.
3. A hat stretcher in which are combined 40 a tubular housing slotted for a portion of its length, a worm screw rotatably secured within the housing, a toothed element extending in part through the housing slot for engagement 45 with the worm screw, and a pair of blocks one secured fast to the housing and the other to the toothed element whereby rotation of the worm screw will effect a shifting movement of the two blocks, one with respect to the other, substantially as described.
4. A hat stretcher in which are combined 50 a tubular housing having a longitudinal slot therein, screw means rotatably secured within the housing, a toothed element extending in part through the housing slot for engagement 55 with the screw means, a block to which the housing is connected fast, a second block having a connection with the toothed element, and means extending from one block toward the other adapted to prevent relative rotation between the two blocks, substantially as described.
5. A hat stretcher in which are combined 60 a pair of blocks each having a transverse opening in alignment with the other, means forming a guideway extending from one block to the other, means on the latter block 65 adapted for sliding movement within the guideway, a tubular guideway having a longitudinal slot extended through the openings in the two blocks and connected fast with one thereof, screw means secured within the housing, and a toothed element connected with the other block and extended through the housing slot for engagement with the screw means whereby the one block may be caused to move toward or from the other with rotation of said screw means, substantially as described.
6. A hat stretcher in which are combined 70 two blocks movable relatively toward and from each other, a pair of ribs depending from one block and bowed to provide between them a cylindrical space, the edges of the ribs remote from the block being straightened and spaced from each other, a tubular housing having a longitudinal slot 75 therein slidably extended within the cylindrical space between the bowed ribs, a toothed element carried between the straightened edges of the ribs and extended in part through the slot of the housing, and screw 80 means rotatably secured within the housing, the second block which forms a mounting for the housing having a guideway in which the ribs are receivable in such a manner as to prevent rotation of one block with respect to the other, substantially as described.
7. A hat stretcher in which are combined 85 two blocks movable relatively toward and from each other, means forming a guideway extending from one block toward the other, means forming a head extending from the other block and slidably receivable within the guideway, a slotted housing carried fast by one block and extended through the other, a toothed element connected with the latter block and extended in part through 90 the slot of the housing, and screw means rotatably secured within the housing in engagement with the toothed element and adapted, when rotated, to effect a movement 95 of one block relative to the other, substantially as described.
8. A hat stretcher in which are combined 100 a base a block fixedly secured to the base, means forming a guideway extending laterally from the block and rested on the base, a second block having means extending therefrom adapted to be slidably received within the guideway, and screw means having operating parts connected with each block 105 adapted to effect a relative movement therebetween, the guideway and parts associated therewith serving to prevent rotation of one block relative to the other, substantially as described.
9. A hat stretcher in which are combined 110 two blocks movable relatively to each other, screw means extending between the two blocks for effecting movement of one toward and from the other, and a mounting whereon one block is slidably carried having a fixed 115

connection with the other block, said mounting being in the form of a housing wherein said screw means is contained in part, substantially as described.

5 10. A hat stretcher in which is combined a pair of relatively movable blocks, tubular means fixedly secured to one block and extended therefrom through the other to pro-

vide a slidable support therefor, and a screw-threaded device longitudinally confined 10 within said tubular means having a screw-threaded engagement with said last named block whereby to move the same relative to the other block, substantially as described.

GEORGE MARGOLIN.
